UNITED STATES PATENT OFFICE.

WILLIAM W. WILKINSON AND JOHN DIXWELL, OF BOSTON, MASSACHUSETTS.

DESIGN FOR A BICYCLE-SEAT.

SPECIFICATION forming part of Design No. 25,951, dated August 18, 1896.

Application filed July 13, 1896. Serial No. 599,055. Term of patent 14 years.

To all whom it may concern:

Be it known that we, WILLIAM W. WILKINSON and JOHN DIXWELL, of Boston, in the county of Suffolk and State of Massachusetts, have invented and produced a new and original Design for Bicycle-Seats, of which the following is a specification.

This invention relates to a new and original design for a bicycle-seat; and it consists in the novel features of shape and configuration hereinafter fully described, and particularly claimed, and clearly illustrated in the drawings.

Figure 1 is a plan view of a bicycle-saddle showing our design. Fig. 2 is a front elevation of the same.

The leading feature of our design consists in the pad or cushion having a depressed central surface and substantially parallel front and rear edges, the ends of the cushion being rounded, the two portions lying in the same plane.

The base piece or plate *a* of the saddle is substantially flat on the under side and has its ends rounded, as at *b*, and its front and

rear edges about parallel with each other and nearly straight, the center of one edge having a slight recess *c*, and the center of the opposite edge having a slight projection *d*.

The cushion or pad conforms in plan outline to the base, but is depressed on the line from the recess *c* to the projection *d*, forming two rounded upper surfaces *e e*, the outer ends of which are rounded and the inner adjacent ends substantially straight. The front and rear edges of the two surfaces *e e* are in a nearly straight line across the saddle.

We claim—

The design for a bicycle-seat, substantially as described.

In testimony whereof we have signed our names to this specification, in the presence of two subscribing witnesses, this 8th day of May, A. D. 1896.

WM. W. WILKINSON.
JOHN DIXWELL.
